(57) **CLAIM**
The ornamental design for a card connector, as shown and described.

(**) Term: **14 Years**

DESCRIPTION

(21) Appl. No.: **29/448,694**

FIG. 1 is a first embodiment of a front, top, and right side perspective view of a card connector that consists of a top cover portion and a bottom portion in assembled condition, showing my new design;

(22) Filed: **Mar. 13, 2013**

FIG. 2 is a front elevation view thereof;

(51) LOC (10) Cl. 13-03

FIG. 3 is a top plan view thereof;

(52) U.S. Cl.

FIG. 4 is a rear elevation view thereof;

USPC **D13/147**

FIG. 5 is a right side elevation view thereof;

(58) **Field of Classification Search**

FIG. 6 is a left side elevation view thereof;

USPC D13/147, 154, 184, 199; 439/64, 79,
439/159-160, 330, 331, 341, 342, 629, 630,
439/636, 660, 607.01, 607.04, 607.05,
439/607.17, 607.25, 607.34, 607.41,
439/607.53, 862, 884, 946

FIG. 7 is a bottom plan view thereof;

See application file for complete search history.

FIG. 8 is a rear, bottom and right side perspective view thereof;

(56)
